Primary Examiner — Susan E Krakower*(74) Attorney, Agent, or Firm* — Armstrong Teasdale LLP(57) **CLAIM**

The ornamental design for a pacifier shield, as shown and described.

DESCRIPTION

FIG. 1 is a perspective view of a pacifier shield of our new design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof; and,

FIG. 7 is a bottom plan view thereof.

The broken lines illustrate environmental structure and form no part of the claimed design.
